CLAIM

The ornamental design for a display screen portion having a graphical user interface for determining optimal times for outdoor activities based on outdoor conditions, as shown and described.

DESCRIPTION

FIG. 1 is a front view of a display screen portion having a graphical user interface for determining optimal times for outdoor activities based on outdoor conditions; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; and, FIG. 7 is a front view of a seventh image thereof.

The outer edge of the portion of the display screen is understood to be congruent with the outer edge of the graphical user interface.
